UNITED STATES PATENT OFFICE

CHAUNCEY L. MITCHELL, OF WINCHESTER, MASSACHUSETTS, ASSIGNOR TO REFRIGERATION CORPORATION OF AMERICA, OF BOSTON, MASSACHUSETTS, A CORPORATION OF MASSACHUSETTS

REFRIGERATOR CONSTRUCTION

Application filed April 4, 1928. Serial No. 267,266.

This invention relates to the construction of a building or chamber in which the walls are insulated to prevent or minimize the passage of heat therethrough and, while adaptable for any purpose where such installation is desirable or necessary, is particularly designed for refrigeration purposes.

The object of the invention is to provide a construction in which the walls of the chamber are composed of section units of standard dimensions, thus enabling the chamber to be constructed and installed in any desired location and of any desired dimensions readily and easily and further enabling the chamber to be taken apart and removed with slight loss whenever desired.

The object of the invention is further to provide a heat insulated wall section unit of novel construction in which the section presents a thick cork board core and thin reinforced cement faces secured to the core in such a manner as to guard against the transmission of heat from one face to the other.

The object of the invention is further to provide such a wall section unit that a plurality of such sections may be assembled and clamped together to form a wall without air spaces between the sections all in a firm and rigid manner.

The object of the invention is further to provide means for securing such wall section units together in a limited space.

The invention has for its further object to provide a construction of heat insulated chamber presenting high insulating properties, composed of standard wall section units and readily assembled in any desired location.

These and other objects and features of the invention will appear more fully from the accompanying description and drawings and will be particularly pointed out in the claims.

The drawings illustrate a preferred form of rectangular heat insulated wall section unit and a simple type of chamber, adapted for refrigeration purposes, built up from such units. But it will be understood that this is merely illustrative of a wide variety of constructions in which the various novel

features of the invention may be embodied.

In the drawings:

Fig. 1 is a view in perspective partially broken away of one form of wall section unit embodying the invention.

Fig. 2 is an enlarged view taken in transverse cross section and with the central portion broken away of the construction shown in Fig. 1.

Fig. 3 is a view in elevation of one form of metal anchor employed.

Fig. 4 is a detail in cross section showing a joint between two adjacent section units.

Fig. 5 is a view in perspective of a portion of a rectangular chamber such as a built-in refrigerator made up of wall section units and embodying further features of the invention.

Fig. 6 is a view in side elevation partially cut away and showing three abutting wall section units with a preferred form of means for clamping and securing them together.

Fig. 7 is a perspective view showing one form of construction at one corner of the chamber.

Fig. 8 is a detail in vertical cross section showing a connection between a vertical and horizontal tie rod.

While, as pointed out, the construction of this invention may be employed with advantage in a wide variety of constructions wherein it is desirable or necessary to insulate against the passage of heat through a chamber wall, it is more particularly designed for built-in refrigerator chambers of relatively large size such as used for commercial purposes. An important feature of the invention resides in the construction of a wall section unit so designed that a very small number of standard sizes of these units will enable practically any desired size and shape of chamber to be readily and easily constructed.

In the construction of a form of chamber such as that illustrated in Fig. 5, two standard sizes of wall section unit, one size for the side walls and the other size for the top and bottom walls, will suffice and by providing section units for the top and bottom walls of

different standard lengths, the size and shape of the chamber may be varied indefinitely. While it may be desirable to provide special sizes of units, it will be evident that the main portion of a chamber of practically any desired size and shape may be built up from a very few standard sizes of wall section units.

A preferred form of wall section unit embodying the invention is illustrated in Figs. 1 and 2. The main heat insulating quality of this unit is secured by the core which is composed of coarsely granulated cork compressed into board form and commercially available. This cork board core 1 is cut to the desired dimensions of the rectangular section unit, for example, substantially 1' in width and of the standard lengths desired for the required height and required width of the chamber. This core should be relatively thick and a thickness of 4" has been found desirable for ordinary refrigerator chamber construction. Each of the faces of the core has secured thereto a relatively thin layer of reinforced cement. As the purpose of these layers is to impart the desired finish to the exterior and interior surfaces of the wall and to assist in preventing passage of air through the wall, and as the walls are not intended to carry any unusual load, these surface layers of reinforced cement may often be quite thin. Such layers $\frac{1}{4}$ " in thickness have been found practical for many purposes, but by increasing the thickness and the character of the reinforce, the strength of the section units may be increased. The reinforce should extend continuously throughout the cement layer and is best embodied in a sheet 2 of reticulated metal such as the expanded sheet metal which is commercially available. This reticulated sheet extends close to, but not quite to, the edges of the surface or face of the cork board. This metal reinforce must be well secured to the cork board both to prevent separation of the cement face from the cork and also to secure a unitary structure which shall present the required strength. But it is of great importance that the securing means employed shall not extend from one face of the unit to the opposite face and thus serve as heat transmitting agencies. The invention therefore provides metal anchors at each face of the unit interlocked with the sheet metal reinforce and extending part way only through the cork board core and embedded in the core and so arranged as to be entirely out of contact with the similar anchors extending from the opposite face. Various anchors may be employed for this purpose. In the construction shown in Figs. 1 and 2, these anchors are in the form of metal staples 3. They are interlocked with the reinforce by having their legs passed therethrough. The legs of the staples extend in various

directions, but in each case at an acute angle to the face of the unit. Thus the staples grip the reinforce firmly to the cork board and as they are arranged so as neither to pass entirely through the cork core nor to come into contact with the staples at the opposite face, there can be no transmission of heat through the anchoring means from one face of the unit to the opposite face. The form of metal anchor is shown in Fig. 3. It is of staple form having the legs 4 provided with a plurality of bars 5. When a staple of this type is employed, it may not be necessary to embed the staples at an acute angle to the face of the unit because of the increased gripping function of the bars.

The cement layer 6 at each face of the unit is formed in the usual manner and fills the interstices of the reinforce and the interstices of the cork board at the surface so that the reinforce is embedded in the cement layer and the cement layer is firmly secured to the cork core. This cement layer is finished smooth at the surface and is preferably made of high grade cement. The edges of the reinforced cement layer, preferably all four edges, but in any event the two longer edges, do not extend quite to the edge of the cork board core, so that the core is left projecting slightly beyond the edges of the cement and metal reinforce, as shown at 7. The edges of the cement are also preferably rounded off at 8.

The edges of the cork board core are thus left projecting so that when the wall is built up and the edges of adjacent sections abut, the sections may be forced together and then clamped, thus compressing the cork at the abutting edges, securing a tight union and eliminating any air spaces, all without danger of straining or injuring the cement faces. When the section units have thus been clamped together with the projecting cork core edges abutting, the little space left between the edges of adjacent cement faces is desirably filled in with cement, as indicated at 9 in Fig. 4, thus presenting a smooth, continuous wall surface.

The wall section units as thus constructed are found to present very substantial strength sufficient for the required purposes. When assembled and clamped together, these units form a wall very highly impervious to the passage of heat. The wall presents a neat and pleasing appearance. A chamber of practically any desired size and shape may be constructed and by providing interior columns and girders all within the chamber and thus insulated by the walls from the exterior, the size of the chamber may be extended indefinitely with the use of standard section units.

It is important that the wall section units shall be drawn tightly together and clamped

in position to form the walls and while within the broader aspects of the invention various means may be employed for this purpose, an important feature of the invention resides in a construction of section unit and an arrangement of tie rods and metal plates by which this result is secured in a simple and efficient manner.

In carrying out this feature of the invention in its preferred form, each section unit has the longer edges of the core each provided with a groove 10 extending longitudinally thereof so that when two sections abut, the grooves of the abutting edges together form a substantially cylindrical bore adapted to receive a tie rod. The core of each section unit is also provided with a plurality of preferably cylindrical bores extending transversely therethrough. Two of these transverse bores 11 are preferably located at a distance from the end edges of the section unit equal to one-half the thickness of the unit. There may be as many intermediate bores 12 as desired, although for a wall section of room height, one intermediate bore is found sufficient. The metal tie rods employed in these various bores are preferably about one-half the diameter of the bores. Thus with tie rods of a diameter of $\frac{3}{8}$ ", the bores are desirably formed of a diameter of $\frac{3}{4}$ ". This enables tie rods extending transversely to each other to pass each other and this result is further facilitated by placing the transverse bores in a different plane from the longitudinal bores but preferably so that the various bores intersect. In the construction illustrated, the transverse bores such as 11 and 12 extend midway of the core, while the grooves 10 forming the longitudinally extending bores are slightly nearer one face of the section unit than the other, this offset being preferably about one-half the bore diameter.

The main portion of a simple type of rectangular refrigeration chamber is shown in Fig. 5 of the drawing. This chamber is shown as composed of but two standard sizes of wall section units, the only difference between these two sizes being that the top and bottom wall units are longer than the side wall units. This is secured by having the side wall units extend between the top and bottom walls, resting on the bottom wall and supporting the top wall, but it is obvious that by employing further standard sizes various relations between the side, top and bottom walls may be secured.

The reinforced cement facing layer at the top of the bottom wall units may be omitted at the end portions upon which the side wall units rest and similarly at the bottom of the top wall units where these units rest upon the side wall units. This brings cork to cork in contact at all abutting areas and is desirable where load and strength conditions permit.

In the construction thus illustrated, three

bottom wall section units 13 are shown which may rest upon a floor. The right, rear and left side walls are each composed of three sections 14, 15 and 16, respectively, and these side wall section units rest at their edges upon the ends of the bottom units. Three top wall section units 17, of the same size as the bottom units 13, rest at their ends upon the upper edges of the side units. It will thus be seen that wherever units abut, either two edges of cork cores come together or an edge of the cork core of one unit comes against the cement face of another unit. Thus when the units are drawn tightly together and clamped, the cork edges in each case are compressed, forming a tight joint and eliminating any air space through the wall. By standardizing the sections with as few units as possible, it follows that the edges of the cork cores will be exposed at various places in the structure, as, for example, at the ends of the top and bottom walls. These exposed edges are preferably covered and protected by metal plates, here shown as the flanges of angle irons employed in clamping and holding the structure together.

The various section units in the preferred construction, as illustrated, are drawn and clamped together by a system of tie rods located in the various bores. Suitable means are provided at the ends of the tie rods to enable this to be done.

It is obvious that in assembling a structure of any substantial size, the tie rods would be of considerable length and when the chamber is constructed inside a building or in a limited space, it is frequently impossible to employ such tie rods. The invention therefore provides another feature in which the tie rods are made in sections threaded at their ends and connected together by unions, the several sections being provided with nuts at their threaded ends so that the wall section units may be set up one at a time, the tie rod sections inserted one at a time and thus one wall section unit drawn up and clamped to the adjacent unit. The wall is then set up section by section with each section drawn up and clamped to the preceding. Such an arrangement is illustrated in Fig. 6 with respect to the side wall section units 14. It will be seen that the tie rod shown is made in sections 18 threaded at the ends and having threaded unions 19 by which the sections may be connected. In setting up such a wall, the section 14 at the left, say, would be set up, the tie rod section 18 inserted, washers 20 placed against the edges of the cork core and nuts 21 threaded on to the rod and screwed up until the washers 20 are pressed into the cork. The section 14 next to the right will then be set up, another tie rod section 18 with the union 19 threaded on its end will be placed in the section and the union screwed on to the projecting end of the tie rod section 18 pro-

- jecting from the first section, then another washer 22 will be placed on the rod section and another nut 23 threaded on to the section and screwed up, thus drawing the sections tightly together. This operation will proceed with the remaining sections. All the transverse tie rods will be treated in the same way. Thus the wall may be erected section by section in a very limited space.
- 10 It is necessary also to draw and clamp the sections together in the opposite direction or vertically. The vertical tie rods placed in the abutting grooves 10 as the sections are set up are employed for this purpose, but when
- 15 the structure is being erected upon a floor, it is usually impractical to thread nuts on to the lower ends of these tie rods. These lower ends may conveniently be secured to a tie rod extending transversely of the bottom, as
- 20 shown in Figs. 5 and 8. For this purpose the vertical tie rod 24 is hook-shaped at its lower end and is hooked over a tie rod such as 25. At its upper end the tie rod passes through a metal plate, herein shown as the
- 25 flange 26 of an angle iron. The hole in this plate through which a tie rod 24 passes is somewhat elongated and a nut 27 is placed on the threaded end of the rod. Consequently by tightening up the nut 27, the bottom wall section, side wall section and top wall section are drawn together and clamped. It will be noted here that the lower and upper edges of the cork core of the side wall unit section 14 abut the surfaces of the bottom
- 30 wall section unit 13 and the top wall section unit 17, thus forming a tight joint and permitting the drawing up of the sections. This construction is repeated at the various joints and preferably as shown the angle iron at the
- 35 top presents a depending flange 28 which covers up and protects the exposed edges of the cork cores of the top wall section units. This construction is preferably applied at all the corners excepting at the bottom, where
- 40 usually a simple flat metal plate 29 is provided at the sides, thus enabling the bottom wall section units 13 to rest flat on the floor or other supporting structure. Tie rods 25 preferably extend also through the bores between the top and bottom wall section units
- 45 and here in these cases nuts are preferably threaded on to both ends of these tie rods, although, if desired, one of the ends may be hooked over the adjacent transverse tie rods.
- 50 Where necessary, the wall section units are transversely grooved as at 30 to provide for tie rods which extend across the units. This tie rod construction with the grooves and bores arranged on the principle described enables a chamber readily and easily to be set up with very little special work being performed, as for such an assembly it is seldom necessary to form any special bores or to make any holes through the reinforced cement faces of the wall section units. The

nuts such as 21 and 23 and the unions 19 are preferably of a size to fit within the bores.

While the invention has thus been described in connection with a simple rectangular form of chamber without any windows or doors being illustrated, it will readily be understood that by following out this general principle any desired size or shape of chamber may be obtained and doors or window openings may readily be provided by the use of special sections and fittings therefor.

70 Preferably, as set forth, the joints between the cement faces of abutting wall section units are filled in with cement, as shown in Fig 4.

80 Such a construction is not only readily and easily set up in a given location, but it may be disassembled with comparative ease, thus rendering the wall section units again available for use in the construction of other chambers with comparatively little expense.

85 Having thus described the invention, what is claimed as new, and desired to be secured by Letters Patent, is:

90 1. A rectangular heat insulated wall section unit comprising a thick core of cork board, a reticulated metal reinforce layer on each face of the core, metal anchors at each face interlocked with the reinforce and extending part way only through and embedded in the core out of contact with the anchors extending from the opposite face and a cement layer on each face of the core with the reinforce and anchors embedded therein.

95 2. A rectangular heat insulated wall section unit comprising the construction defined in claim 1, in which the metal anchors are in the form of staples interlocked with the reinforce by having their legs passed therethrough and with the legs extending at an acute angle to the face.

100 3. A rectangular heat insulated wall section unit comprising the construction defined in claim 1, in which the metal anchors are in the form of staples interlocked with the reinforce by having their legs passed therethrough and with the legs extending at an acute angle to the face and the legs of the staples at each face extending in a plurality of different directions.

110 4. A rectangular heat insulated wall section unit comprising a thick core of cork board, a reticulated metal reinforce layer on each face of the core, metal anchors at each face interlocked with the reinforce and having barbed legs extending part way only through and embedded in the core out of contact with the anchors extending from the opposite face and a cement layer on each face of the core with the reinforce and anchors embedded therein.

115 5. A rectangular heat insulated wall section unit comprising the construction defined in claim 1 in which the two longer edges of the

core project slightly beyond the edges of the cement and metal reinforce.

6. A rectangular heat insulated wall section unit comprising the construction defined in claim 1 in which the two longer edges of the core project slightly beyond the edges of the cement and metal reinforce, and in which the said longer edges of the core present a groove extending longitudinally thereof so that when two sections abut a bore is formed to receive a tie rod.

7. A rectangular heat insulated wall section unit comprising the construction defined in claim 1, in which the edges of the core project slightly beyond the edges of the cement and metal reinforce.

8. A rectangular heat insulated wall section unit comprising a thick core of cork board, and a thin layer of reinforced cement secured to each face of the core with the edges of the core projecting slightly beyond the edges of the reinforced cement and with the longer edges of the core presenting a groove extending longitudinally thereof so that when two sections abut a bore is formed to receive a tie rod.

9. A plurality of rectangular wall section units having thick resilient cores and thin cement faces with the cores projecting slightly at the lateral edges and with bores extending laterally through the cores, threaded clamping sectional rods in said bores, nuts threaded on said rods at the joints between the sections, and unions threaded to and adjustably connecting adjacent rod sections within the bores whereby in succession and separately each wall section unit may be drawn up against and clamped tightly to the adjacent unit.

10. A rectangular heat insulated wall section unit comprising a thick core of resilient heated insulated material and a thin layer of reinforced cement secured to each face of the core with the core projecting slightly beyond the reinforced cement faces at the longer edges, the said longer edges of the core each presenting a groove extending longitudinally thereof so that when two sections abut, a bore is formed to receive a tie rod, the said core also having bores extending therethrough transversely of the longer edges, the said grooves and bores offset but intersecting to enable the tie rods in the bores to cross each other.

11. A heat insulated chamber having a top wall and a side wall each composed of rectangular section units each having a thick cork board core and cement faces with the core projecting slightly at the lateral edges and in the case of the side wall section units at the top edges also, the ends of the top wall section units resting on the top edges of the side wall section units, a metal plate on top of the ends of the top wall section units, the abutting edges of the cores of the side wall section units presenting grooves forming

vertical bores, tie rods in said bores extending through the metal plate, means at the ends of the tie rods for drawing together and clamping the top wall section units, the side wall section units and the metal plate, and means for drawing together and clamping adjacent top wall section units and adjacent side wall section units.

12. A heat insulated chamber having a top wall and a side wall each composed of rectangular section units each having a thick cork board core and cement faces with the core projecting slightly at the lateral edges and in the case of the side wall section units at the top edges also, the ends of the top wall section units resting on the top edges of the side wall section units, an angle iron having one flange on top of the ends of the top wall section units and the other flange extending down over the exposed edges of the top wall section units, the abutting edges of the cores of the side wall section units presenting grooves forming vertical bores, tie rods in said bores extending through the top flange of the angle iron, means at the ends of the tie rods for drawing together and clamping the top wall section units, the side wall section units and the angle iron, and means for drawing together and clamping adjacent top wall section units and adjacent side wall section units.

13. A heat insulated chamber having a top wall, a bottom wall and a side wall each composed of rectangular section units each having a thick cork board core and thin reinforced cement surfaces with the core projecting slightly at the edges, the bottom edges of the side wall units resting on the ends of the bottom wall units and the ends of the top wall units resting on the top edges of the side wall units, a metal plate on top of the ends of the top wall units, the abutting edges of the cores of the side wall units presenting grooves forming vertical bores, a tie rod extending transversely through the cores of the bottom wall units beneath the side wall, tie rods in said vertical bores connected to said transverse tie rod and extending through said metal plate, and means on the upper ends of said vertical tie rods for drawing together and clamping the top wall, side wall, bottom wall, metal plate and transverse tie rod.

14. A heat insulated chamber comprising the construction in claim 13, in which the vertical tie rods are connected to said transverse tie rod by means of hooked ends on the vertical tie rods embracing the transverse tie rod.

15. A heat insulated chamber comprising the construction defined in claim 13, together with additional tie rods extending transversely through the cores of the top wall, side wall and bottom wall units and means on the ends of all the transverse tie rods for

drawing together and clamping the units of all three walls.

16. A heat insulated chamber comprising the construction defined in claim 13, in which the said metal plate is in the form of an angle iron, one flange of which is located on top of the ends of the top wall units and the other flange of which extends down over the exposed edges of the top wall units.

10 In testimony whereof, I have signed my name to this specification.
